REVOLVING DOOR SPEED CONTROL

Thurloe M. Hagenbook, Evansville, Ind., assignor
to International Steel Company, Evansville,
Ind., a corporation of Indiana

Application September 10, 1932
Serial No. 632,627

5 Claims. (Cl. 20—18)

My invention relates broadly to revolving doors and more particularly to a speed control for attachment for revolving doors.

One of the objects of my invention is to provide a construction of speed control device for attachment to revolving doors of various types for controlling the speed of revolution of the revolving door and increasing the safety of operation.

10 Another object of my invention is to provide a simplified construction of speed control for revolving doors which may be inexpensively manufactured on a quantity production basis and utilized for precision operation in the control of 15 revolving doors of various makes.

Still another object of my invention is to provide a construction of speed control hardware for revolving doors having means for engaging or disengaging the rotary structure of 20 the revolving door and governing the speed of the revolving door when in engaged position.

A further object of my invention is to provide a construction of centrifugal governor for 25 revolving doors wherein substantial load is added to the door under conditions where the rate of speed at which the door is operated increases beyond a predetermined value.

A still further object of my invention is to provide an attachment capable of engaging the 30 upper pintle of the revolving door and establish a geared connection with a centrifugal governor and friction brake device for controlling the speed of operation of the revolving door within predetermined limits.

35 Another object of my invention is to provide a construction of centrifugally operated clutch for a governor for revolving doors having means for rendering a friction brake effective when the speed of rotation of the revolving door tends to 40 exceed a predetermined rate.

Other and further objects of my invention reside in the construction of friction brake revolving door speed control as set forth more fully in the specification hereinafter following by reference to the accompanying drawings, in which:

Figure 1 is a cross-sectional view taken through the revolving door speed control of my invention with some of the parts illustrated in side elevation; Fig. 2 is a side elevational view of 50 the revolving door speed control showing the supporting rails constituting the trolleys and the socket bearing for the upper portion of the revolving door illustrated in cross-section and looking in the direction of arrow A of Fig. 1; Fig. 3 is a horizontal sectional view of the re-

volving door speed control device of my invention taken on line 3—3 of Fig. 1; Fig. 4 is a horizontal sectional view taken through the speed control on line 4—4 of Fig. 1 on an enlarged scale; Fig. 5 is a cross-sectional view taken through the speed control on line 5—5 of Fig. 1; Fig. 6 is a cross-sectional view taken through the speed control on line 6—6 of Fig. 1; Fig. 7 is a side elevation of the ratchet mechanism employed in connection with the centrifugal governor mechanism in the revolving door speed control device of my invention; and Fig. 8 is a schematic view showing the manner in which the revolving door is assembled for connection with the speed control device.

Referring particularly to the drawings, reference character 1 designates the wings of the revolving doors arranged to revolve around the central axis 2 immediately below the rails 3 constituting the trolley support for the revolving 75 doors. The wings 1 of the revolving doors are suspended from the rails 3 by means of roller members 4 journaled on the ends of shaft 5 connected through support 6 with member 7 which engages the upper rail 8 of the revolving doors. The upper rail 8 is provided with socket member 9 within which annular member 10 is seated for housing the annular members 11 and 12 having ball races for guiding ball bearings 14 therebetween. The annular member 10 has upwardly projecting cylindrical walls 10a and 10b between which, the annular members 11 and 12 are confined and into which the annular member 16 projects and rests upon the upper portion of the annular ring member 12. The member 16 is screw threaded at 16a to receive the screw threaded end of the tubular member 2 as shown. The upper portion of members 16 is provided with a socket 16b into which there extends the cylindrical liner 17. The cylindrical liner 17 provides a socket which is adapted to receive the spring pressed pin 18. The spring pressed pin 18 is chamfered at 18a to permit ready insertion or removal of pin 18 from the socket formed interiorly of the liner 17. The pin 18 is mounted within a cylindrical guide 19 which projects from the lower plate 20 forming part of the housing of the speed control device. The cylindrical guide 19 has a screw device 21 extending through one side thereof with a pin 22 from the end of the screw device projecting into a socket 23 in one side of the projectible pin 18 so that pin 18 is free to move vertically against the resistance offered by coil spring 30. It will be observed that the upper portion of annular member 16 has a

110

115

120

beveled surface represented at 16c which enables the revolving door assembly to be interconnected with the speed control governor mechanism by rolling the revolving doors on the trolleys to a 5 position where the beveled surface contacts with the chamfered edge 18a of pin 18, thereby raising pin 18 and allowing the pin to drop into the socket formed by the liner 17. The revolving door structure is thus centered with respect to the 10 governor mechanism, and the gear teeth 16d on the periphery of the annular member 16 are brought into mesh with the gear teeth on gear 32. Gear 32 is carried by stub shaft 33 which is journaled in ball bearings 34 and 35. Ball bearings 15 34 are mounted in races supported in plate 20. Ball bearings 35 are mounted in races supported in casting 36 which extends in a position substantially chordal to the casing within which the speed control mechanism is housed. The casting 20 20 36 which is illustrated more clearly in Figs. 2 and 5, is secured to plate 20 by means of screws 36a and is provided with downwardly depending lugs 37 through which set screws 38 pass and engage rails 3 forming part of the stationary equipment 25 25 of the revolving door. In order to further mount the governor rigidly with respect to the stationary frame structure beneath which the revolving door moves, I provide the casting 39 beneath the governor housing and substantially chordal 30 30 to the governor housing and connected thereto through screw members 39a. The casting 39 has depending lugs 40 through which the securing screws 41 pass, which screws grip rails 3 as represented in Fig. 6 thereby insuring a rigid mounting 35 35 for the governor housing immediately above the rails 3.

The transversely extending plate 20 has the cover member 31 secured thereto by means of bolt members 42. The cover member 31 and plate member 20 is recessed as indicated at 31a and 20a to receive roller bearing guide rings represented at 43 and 44 respectively. A stub shaft 45 is journaled vertically through casing 31 and plate 20 by means of annular members 46 and 47 aligned with respect to the annular members 43 and 44 by means of conical shaped roller bearings 48 and 49 as shown. Shaft 45 is provided with gear teeth 50 on the lower projecting end thereof adapted to mesh with gear 51 carried by stub shaft 50 50 53. It will be seen that rotation of the revolving doors 1 serves to impart rotary movement to member 16 whereby gear 16d drives gear 32 thereby rotating shaft 33 in the bearings 34 and 35 and driving gear 51 which in turn drives vertical shaft 55 55 45 through gear teeth 50 thereon. Shaft 45 has a sleeve 52 secured thereon concentrically within the frame 53 of the friction discs. The shaft 45 is diametrically apertured for the passage of pin 54. The aperture 55 in shaft 45 through which 60 60 pin 54 extends is elongated vertically so that the frame 53 in the friction wheel is free to move vertically within limits offered by the aperture 55. A coil spring 56 is disposed within the central socket of shaft 45 and exerts a continuous force 65 65 against pin 54 and the adjusting screw head 57. By adjusting screw head 57 downwardly against coil spring 56 the vertical thrust of the frame 53 of the friction wheel is resisted so that the load which is added to the revolving doors at a predetermined rate of speed may be accurately controlled. The friction wheel 53 has a friction face 58 secured thereto adapted to be pressed into engagement with the friction face 59 of the casing 31 for retarding the rotation of the revolving doors and holding the doors to the predetermined

speed in accordance with the condition of centrifugal force which is established as the doors revolve. The sleeve 52 carried by the frame of the friction wheel 53, has clutch teeth 52a directed downwardly for normally engaging clutch teeth 60 projecting upwardly from a hub 61 on rotatable disc 62. The rotatable disc 62 has a plurality of upstanding lugs 62a thereon disposed in diametrically opposite positions on the disc 62 and serve as pivots for bell cranks 63. The bell cranks each carry weights 64 on the extremities thereof, which weights are free to move in radial planes under the action of centrifugal force. The bell cranks have pressure feet 65 on opposite extremities thereof which engage the lower face of the frame of the friction wheel 53. Under the action of centrifugal force the weights 64 move outwardly within the hollow interior of the housing 31 and operate to force friction wheel 53 upwardly so that friction surface 58 engages beveled surface 59 in housing 31 for gradually increasing the load on shaft 45, and holding the shaft and the associated gear train and the revolving doors to the predetermined speed. The various degrees of loading on the revolving doors depend upon the amount of centrifugal force which is established. When the rate of movement is interfered with, the flywheel 62 acts as a driver, thus causing clutch 60 to raise clutch 52a. This action brings 58 in contact with 59 and will stop the doors, serving as a safety device, for in case of any object or person getting caught between the doors and wall the doors may be quickly stopped thus avoiding injury to property and people. The brake acts very quickly where a person or object stops the door and will prevent accidents which could occur if the brake did not act promptly. When the speed of the revolving door is reduced, the weight of the friction wheel 53 and the force of spring 56 acting upon pin 54 is such as to restore the bell cranks to a position immediately adjacent the upper surface of rotatable disc 62, thus returning the weights 64 to a position in which changes in speed will produce changes in angular position of the weights 64. The speed control may be adjusted for operation at selected rates of speed by adjusting screw threaded member 57 against spring 56 which bears against diametrically extending rod 54, so that the frictional load will be rendered effective at a predetermined speed. The trolley mechanism operating upon the guide rails permits the doors to be moved over to the side of opening, thereby giving a free opening so that large objects may be taken through the doors. The trolley only carries the weight of the doors. When the doors must be moved out of central position, the ejector rod 66 is given a quick vertical movement by means of the projecting lever 67 extending through slot 65 in the vertically disposed tube 2. The ejector rod 66 passes through a bushing, as indicated at 69, which is placed in the end of tube 2. Rod 66 has a diameter of approximately $\frac{1}{8}$ " and a length terminating short of the pin 18. Rod 66 always terminates beneath pin 18 allowing the installation of the equipment on doors of different heights and permitting installations to be made on old doors now in use. Upward movement of rod 66 forces pin 18 out of socket 17, enabling gear 16b to be disengaged from gear 32, so that the entire revolving door structure may be shifted on the trolley away from the speed control mechanism.

When it is desired to engage the speed control mechanism with the revolving door structure, the revolving doors are moved on the trolley mecha-

nism to a position in which the pin 18 rides on beveled surface 16c of member 16 and after being depressed vertically drops into the socket formed by sleeve 17, thereby maintaining the gears in mesh and enabling the speed control to directly function under control of the movement of the doors. In order to maintain the parts of the speed control in lubricating condition, I provide a port 69 through shaft 45 which may be closed 10 by any suitable oil cup or device, represented generally at 70, for supplying lubricant to the moving parts of the speed control.

It will be seen that under normal conditions the rotatable disc 62, the frame 53 of the friction wheel and the rotatable shaft 45, rotate as a unit through the clutch connection formed by teeth 52a and 60. Under conditions of increase in speed, however, the load due to the vertical movement of the friction wheel of which 53 forms a part, is increased as the coupling between rotatable disc 62 and shaft 45 is decreased but the clutch teeth 60 and 52a are never disengaged. The loading of the doors will prevent racing through them. It is not intended for the speed control to exert a force great enough to cause the doors to collapse, but to add a load so as to discourage the desire to race, thereby making the doors safe for everybody. The clutch is always engaged except when the door decelerates. 30 When the door moves slower than the flywheel, the clutch partially disengages when the upper jaws raise.

It will be observed that rotatable disc 62 is weighted at its periphery so that the flywheel 35 acts as a regulator and continues to drive the revolving doors by release of the kinetic energy stored therein after the driving force on the doors has been released. Allowance is made in the action of the brake system to permit sufficient movement of the revolving doors to prevent injury to persons or objects caught between the ends of the door wings and the frame. The character of gripping action brought about by the brake system is such, that a sufficient yielding action is obtainable to prevent injury to persons or objects. If the speed of rotation is increased beyond a safe value and the door comes to rest at the limit of the peak speed, the brake 45 will automatically allow the door to be released and to be revolved freely.

The structure of my invention has been found to be highly practical in manufacture, production and operation, and while I have described my invention in certain preferred embodiments, 55 I desire that it be understood that modifications may be made and that no limitations upon my invention are intended other than are imposed by the scope of the appended claims.

What I claim as new and desire to secure by 60 Letters Patent of the United States is as follows:

1. In a revolving door construction, an overhead track, a casing mounted in a stationary posi-

tion adjacent said track, a vertical shaft carrying radial door-wings, said shaft being rotatably mounted and shiftable along said track into and out of position adjacent the casing, and means in the casing for controlling rotation of the shaft operatively connected with the shaft when the shaft is in a set position adjacent the casing. 80

2. In a revolving door construction, an overhead track, a casing mounted in a stationary position above said track, a carriage shiftable along said track, a vertical shaft carrying radial door-wings and journaled through said carriage and movable therewith into and out of position beneath said casing, means in said casing for controlling rotation of said shaft operatively connected with the shaft when the shaft is in position beneath the casing, and means for releasably securing the shaft and carriage against movement out of position beneath the casing. 85

3. In a revolving door construction, an overhead track, a shaft carrying radial door-wings, said shaft being rotatably mounted and shiftable along said track into and out of position to rotatably mount the door in a doorway and means for controlling the rotation of said shaft mounted 100 in a stationary position adjacent said track and operatively connected with the shaft when the shaft is moved into the said position to rotatably mount the door. 90

4. In a revolving door construction, an overhead track, a stationary casing above said track, a carriage shiftable along said track, a vertical shaft carrying radial door-wings and journaled through said carriage and movable therewith into and out of a set position beneath the casing, a 110 gear upon the upper end portion of said shaft, means in said casing for controlling rotation of said shaft having actuating mechanism including a gear meshing with the gear of said shaft when the shaft is in position beneath the casing, and 115 means for releasably securing the shaft and carriage in place beneath the casing. 105

5. In a revolving door construction, an overhead track, a stationary casing above said track, a carriage shiftable along said track, a vertical 120 shaft carrying radial door-wings and journaled through said carriage and movable therewith into and out of a set position beneath the casing, a gear upon the upper end portion of said shaft, means in said casing for controlling rotation of 125 said shaft having actuating means including a gear meshing with the gear of the shaft when the shaft is in position beneath the casing, the gear of the shaft having a concentrically located socket open at its upper end, a latch pin slidably 130 carried by said casing for vertical movement into and out of a depressed position for engaging in said socket to releasably secure the shaft and carriage in place beneath the casing with the gears meshing, and a spring yieldably holding the pin 135 in its depressed position. 140

THURLOE M. HAGENBOOK.
